[57] **CLAIM**

The ornamental design for a combined ceiling fan and light fixture, as shown and described.

DESCRIPTION

FIG. 1 is a front perspective view of a combined ceiling fan and light fixture incorporating my ornamental design;

FIG. 2 is a rear view of the combined ceiling fan and light fixture of FIG. 1;

FIG. 3 is a side view of one side of the combined ceiling fan and light fixture of FIG. 1;

FIG. 4 is a side view of an opposite side of the combined ceiling fan and light fixture of FIG. 1;

FIG. 5 is a bottom view of the combined ceiling fan and light fixture of FIG. 1, on a reduced scale; and,

FIG. 6 is a top view of the ceiling fan of FIG. 1, on a reduced scale.

The fan blades have been shown broken-away in FIGS. 1-6 to indicate indeterminate length.
